METHOD FOR PRODUCING INTERMITTENT EFFECTS AND SYSTEM THEREFOR

Ward W. Watrous, Jr., Bloomfield, N. J., assignor, by mesne assignments, to Westinghouse Electric and Manufacturing Company, East Pittsburgh, Pa., a corporation of Pennsylvania

Application September 30, 1933, Serial No. 691,637

5 Claims. (Cl. 250—36)

The invention relates to a new method and means for intermittently operating an external means. More particularly the invention is directed to the operation of an external means which requires a relatively high potential for the operation thereof and which operation shall be at a relatively low frequency. One of the fields where my invention finds especial application is that field of sign or other similar type of illumination where a gas-filled lamp is generally employed and where the frequency of lighting desired is relatively low.

Warning signals, some advertising and other signs may be briefly characterized as flashing signs. This type of sign depends for its effect upon alternate flashing and extinguishing of a suitable light source, which upon illumination, may be of any desired color characteristic. The length of time that the light source is flashed and the interval between flashes are not the same in all fields, but in each instance depend upon the particular functions of the flashing. In some beacons for example, the time of flashing as well as the time interval between flashes may be relatively short, whereas in some advertising signs the time of the flashing may be relatively long and the time interval between flashes may be relatively short.

My invention may be used in any one of these different fields. It also finds utility in other fields which I have not mentioned because they suggest themselves and light flashing appears to be satisfactory for illustrating my invention.

In addition a light flashing circuit is that with which I am particularly concerned, and especially light flashing where a high potential is required. My invention, however, is not limited to high potential flashing or to gas filled tubes, they merely serve to clearly illustrate my invention.

Briefly stated my invention is directed to a system and method which includes charging a plurality of condensers. When one of said condensers has attained a predetermined charge, it initially operates a switching means which allows the other condenser to discharge. The discharge current of the second condenser passes through the primary of a transformer and the electrical energy is transformed so that the current in the secondary of the transformer is lower than that in the primary and the voltage across the secondary is higher than that across the primary. The electrical energy in the secondary is employed to operate any desired mechanism such as a lamp, depending upon what is desired. The length of time for charging the condenser that

initially operates the switch determines the time interval between flashes and the time of discharging the condenser that supplies the current in the primary of the transformer determines the length of time of each flash.

An object of my invention is to provide a new method of producing intermittent effects.

Another object of my invention is to provide a new method of intermittently flashing a light source.

A further object of my invention is to provide a new method of intermittently flashing a light source requiring a higher electrical potential for flashing the same than that provided by the initial electrical energy supply.

A still further object of my invention is to provide a new electrical system for producing intermittent effects.

Another object of my invention is to provide a simple and efficient electrical system for intermittently flashing a light source.

A further object of my invention is to provide an easily constructed and rugged apparatus which may be attached directly to a low voltage supply source for intermittently flashing a high voltage light source.

A still further object of my invention is to provide a rugged system containing no essential moving parts, but which may contain moving parts merely for variation purposes, for intermittently flashing a light source at a potential higher than the initial potential supplied.

Another object of my invention is to provide a system for intermittently flashing a light source, with the frequency of discharge in the lamp being independent of the frequency of the input current supplied.

A further object of my invention is to provide an intermittent flashing system which is stable in operation and consumes only a small amount of current so that it is practical to employ batteries as the source of electrical energy.

Other objects and advantages of my invention will be readily apparent from the following description and drawing, wherein

Figure 1 represents a novel circuit diagram embodying my invention;

Figure 2 represents another novel circuit diagram embodying my invention and is a modification of the circuit illustrated in Figure 1.

One aspect of my invention is the novel circuit arrangement illustrated in Figure 1. The invention comprises an input circuit consisting of a plurality of batteries 10 connected in series, a variable condenser 11 and a variable resistance 55

- 12 all in electrical series relationship. Instead of the train of batteries, I may employ a direct current derived directly from a direct current generator or by rectifying alternating current. 5 However, because the amount of current required from the source of electrical energy is relatively low, I have found that it is possible to employ batteries.

10 A conductor 13 has one end thereof connected to one side of the condenser 11 and its other end connected to the end positive terminal of the train of batteries. A conductor 14 has one end connected to a negative terminal of said train of batteries and its other end connected to one 15 side of the resistance 12. The other end of the resistance 12 is not permanently connected to any conductor, but a movable contact 15 is adapted to slide over said resistance. The contact 15 is connected to one end of a conductor 16 and 20 the other side of said condenser 11 is connected to the other side of said conductor. The ohmic value of said resistance 12 depends upon the voltage between said positive and negative terminals of said train of batteries as well as the 25 rate at which it is desired to charge the condenser 11. The resistance 12 has the additional functions of preventing excessive current drain from the batteries and also permitting the potential of the condenser to fall when the condenser 30 is discharged.

Cooperating with said input circuit is a discharge circuit including the condenser 11 as one of the elements thereof. The discharge circuit comprises the condenser 11, a switch 17 and a 35 primary winding 18 of a transformer 19 all in electrical series relationship. Although a mechanical switching means or some other type of electrical switching means may be employed in the discharge circuit, some of which may readily 40 suggest themselves, I employ a tube 17 comprising an anode 20, a cathode 21 and a starting tip 22 all located within an envelope containing a suitable quantity of a rare gas. The tube may be so constructed that when a predetermined 45 potential is applied between the anode 20 and the cathode 21, it will be insufficient to cause a discharge therebetween. When a predetermined and relatively low potential is applied between the anode 20 and the starting tip 22, it 50 will cause a discharge therebetween to ionize the gas within the envelope of the tube. When said ionization occurs, the resistance between the anode 20 and the cathode 21 is decreased so that the predetermined potential applied 55 therebetween is sufficient to cause a discharge therebetween. Thus the tube embodies an anode 20 and starting tip 22 which act as an initiator or trigger for the switch so that the main switching may be accomplished by a discharge between 60 the anode 20 and the cathode 21.

A conductor 23 has one end connected to the anode 20 and its other end to that side of the condenser 11 connected to the end positive plate of the train of batteries 10. A conductor 24 has 65 one end connected to the other side of said condenser 11 and its other end connected to one end of the primary 18 of the transformer 19. A conductor 25 has one end connected to the other end of the primary 18 and its other end to the 70 cathode 21.

In order that the trigger comprising the anode 20 and the starting tip 22 may operate so that the main switching between the anode 20 and the cathode 21 may take place, I provide a trigger circuit including the switch 17, and a variable 75

condenser 26 in electrical series relationship. A conductor 27 has one end connected to the anode 20 and its other end to the condenser 26. A conductor 28 has one end connected to the other side of the condenser 26 and its other end to the starting tip 22.

The condenser 26 is an element of a charging circuit including the entire train of batteries 10, the condenser 26 and a variable resistance 29 all in electrical series relationship. One side of 10 the condenser 26 is connected to the end positive plate of the train of batteries 10 through the conductors 13, 23, and 27. The other side of the condenser is connected to one end of the variable resistance 29 by a conductor 30. A 15 conductor 31 has one end connected to the end negative terminal of the train of batteries 10 and its other terminal to the movable contact 34 of the resistance 29.

A secondary 32 is employed in the transformer 20 19 which is electromagnetically coupled with the primary winding 18 for transforming the electrical energy in the discharge circuit when current flows therethrough. The ratio of the number of turns in the primary to the number of turns in the secondary of the transformer depends 25 upon the voltage required at the terminals of the secondary, across which is applied a load as for example, a gas filled lamp requiring a thousand or more volts to operate the same. I find 30 that in operating a gas-filled lamp with cold electrodes better results are obtained by employing a variable condenser 33 set at appropriate capacity across the terminals of the primary winding 18.

The operation of the apparatus illustrated in Figure 1 is as follows: Electrical energy is supplied to the condenser 11 by the batteries 10 through the variable resistance 12. The variable resistance does serve to some extent to determine the time required to fully charge the condenser 11. However, although this function is of major importance other primary functions of the resistance 12 are to prevent excessive current drain from the batteries and to permit the potential 40 to fall sufficiently when the condenser 11 is discharged. When the condenser 11 is fully charged, the potential between the anode 20 and the cathode 21 of the switch 17 is insufficient to cause a discharge therebetween. The condenser 26 is 45 charging at the same time that condenser 11 is charging. The condenser 26 is charged by the train of batteries 10 through the resistance 29. The resistance 29, like the resistance 12, prevents 50 excessive drain from the batteries 10. The resistance 29 also determines the time of charging of the condenser 26. When the condenser 26 has attained a predetermined charge, the potential between the anode 20 and the starting tip 22 is sufficient to cause a discharge therebetween. The resistance 29 and the capacity of the condenser 26 are so chosen that the condenser 11 is 55 fully charged before the condenser 26 has acquired a potential sufficient to cause a discharge between the anode 20 and starting tip 22. When 60 the discharge occurs between the anode 20 and starting tip 22, the gas within the tube 17 is ionized so that the resistance between the anode 20 and cathode 21 is sufficiently decreased whereupon the potential between these electrodes, by 65 virtue of the fully charged condenser 11, is sufficient to cause a breakdown therebetween.

When this occurs the electrical energy stored in the condenser 11 passes through the switch 17 and the primary winding 18 of the discharge cir- 70 75

cuit. The electrical energy passing through the primary winding 18 is transformed so that the potential between the terminals of the secondary 32 may be a thousand volts or more to operate 5 a load, as for example, a cold electrode gas filled lamp.

Discharge between the anode 20 and starting tip 22 is maintained for a period of and until the extinction voltage between these two electrodes is reached upon discharge of the condenser 26. The resistance 29 permits the potential between these electrodes to fall to a value equal to the extinction potential therebetween. Thus the resistance 29 prevents the condenser 26 from 15 again acquiring a charge sufficient to cause breakdown between the starting tip 22 and anode 20 until a time period after discharge between anode 20 and cathode 21 has terminated. The length of time of each discharge through the lamp depends upon the capacity of the condenser 11. When the charge from the condenser 11 is dissipated to the extent that the extinction voltage of the tube is reached, the lamp discharge terminates and there is an interval of time during 25 which there is no discharge in the lamp or any current flow in the discharge circuit.

During this time the condensers 11 and 26 are again being charged. Again, when the condenser 26 reaches a predetermined charge, discharge is 30 initiated in the switch 17 which discharge allows a discharge of the condenser 11 in the discharge circuit.

When the condenser 11 has been discharged the potential between the anode 20 and the cathode 21 has been considerably reduced so that it is not high enough to maintain a discharge therebetween. The discharge is, therefore, ended and in order that it may not always have a potential greater than the extinction potential and so 40 that the discharge may not be continuous the resistance 12 is provided to limit the rate of charging. The resistances 12 and 29 are so chosen that the rate of charging the condenser 11 is greater than the rate of charging the condenser 45 26, but the rate of charging the condenser 26 is not so high that once the discharge is started between the anode 20 and cathode 21, it will be maintained continuously. Since the discharges between the anode 20 and cathode 21 are for limited times only, it is evident that the time required 50 to charge the condenser 26 to a predetermined potential is at least as great and preferably greater than the time required to fully charge the condenser 11. The discharge of the condenser 11 depends upon the trigger action caused by the 55 discharge of the condenser 26 and the time interval between discharges of the condenser 11 depends upon the time required to charge the condenser 26.

The system illustrated in Figure 2 is essentially 60 the same as that illustrated in Figure 1. Instead of employing the switch 17 shown in Figure 1, there is employed a switch 40 comprising a main anode 41, a cathode 42 and a starting anode 43. The switch is the same as that described in the 65 United States Patent 1,871,279 issued to Harvey C. Rentschler, August 9, 1932. The anode 41 and cathode 42, and the starting anode 43 are connected respectively to the conductors 25, 23 and 28.

The end positive terminal, a positive terminal 70 and the end negative terminal of the train of batteries 10 are connected respectively to the conductors 31, 14 and 13. In this system discharge is first initiated between the starting

anode 43 and the cathode 42 whereupon the condenser 11 discharges between the main anode 41 and cathode 42.

Thus it is apparent that both of my novel systems may be employed where light flashes are to be produced at intervals, which intervals between flashes are determined by the capacity of the condenser 26 and the resistance 29.

The invention is susceptible to numerous modifications and is to be limited only by the prior art 10 and not by the exact system shown and described.

What is claimed:

1. A system for producing high-voltage intermittent effects comprising a condenser and means connected thereto for accumulating an electrical charge therein of a predetermined value, a gaseous conduction device having a plurality of electrodes therein, two of said electrodes being connected to said condenser and having such a space relationship that when the charge in the condenser reaches the said predetermined value a discharge is initiated between said two electrodes in said gaseous conduction device, a second condenser, means for accumulating a greater charge in said second condenser than in said first condenser, one of said first mentioned electrodes and the remaining electrode in said gaseous conduction device being connected to said second condenser, said last mentioned electrodes having such a space relationship that the accumulated charge in said second condenser is insufficient to produce a discharge therebetween in said gaseous conduction device when no discharge occurs between said first two electrodes but sufficient to produce a discharge therebetween when a discharge takes place between said first two electrodes.

2. A system for producing high-voltage intermittent effects comprising a condenser and means connected thereto for accumulating an electrical charge therein of a predetermined value, means for varying the rate of charging of said condenser, a gaseous conduction device having a plurality of electrodes therein, two of said electrodes being connected to said condenser and having such a space relationship that when the charge in the condenser reaches the said predetermined value a discharge is initiated between said two electrodes in said gaseous conduction device, a second condenser, means for accumulating a greater charge in said second condenser than in said first condenser, one of said first mentioned electrodes and the remaining electrode in said gaseous conduction device being connected to said second condenser, said last mentioned electrodes having such a space relationship that the accumulated charge in said second condenser is insufficient to produce a discharge therebetween in said gaseous conduction device when no discharge occurs between said first two electrodes but sufficient to produce a discharge therebetween when a discharge takes place between said first two electrodes.

3. A system for producing high-voltage intermittent effects comprising a condenser and means connected thereto for accumulating an electrical charge therein of a predetermined value, a gaseous conduction device having a plurality of electrodes therein, two of said electrodes being connected to said condenser and having such a space relationship that when the charge in the condenser reaches the said predetermined value a discharge is initiated between said two

electrodes in said gaseous conduction device, a second condenser, means for accumulating a greater charge in said second condenser than in said first condenser, means for varying the rate 5 of charging said second condenser, one of said first mentioned electrodes and the remaining electrode in said gaseous conduction device being connected to said second condenser, said last mentioned electrodes having such a space relationship that the accumulated charge in said second condenser, is insufficient to produce a discharge therebetween in said gaseous conduction device when no discharge occurs between said first two electrodes but sufficient to produce a 10 discharge therebetween when a discharge takes place between said first two electrodes.

4. A system for producing high-voltage intermittent effects comprising a condenser and means connected thereto for accumulating an electrical 20 charge therein of a predetermined value, a gaseous conduction device having a plurality of electrodes therein, two of said electrodes being connected to said condenser and having such a space relationship that when the charge in the condenser reaches the said predetermined value a 25 discharge is initiated between said two electrodes in said gaseous conduction device, a second condenser, means for accumulating a greater charge in said second condenser than in said first condenser, means for varying the rate of charging said second condenser, one of said first mentioned electrodes and the remaining electrode in said 30 gaseous conduction device being connected to said second condenser, said last mentioned electrodes,

having such a space relationship that the accumulated charge in said second condenser is insufficient to produce a discharge therebetween in said gaseous conduction device when no discharge occurs between said first two electrodes but sufficient to produce a discharge therebetween when a discharge takes place between said first two electrodes. 5

5. A system for producing high-voltage intermittent effects comprising a condenser, a battery 10 connected to said condenser for charging the same to a predetermined potential, a gaseous conduction device having a plurality of electrodes therein, two of said electrodes being connected to said condenser and having such a space relationship 15 that when said condenser is charged to the predetermined potential a discharge in said gaseous conduction device is initiated between said certain electrodes; a second condenser connected to said battery for accumulating a greater charge 20 in said second condenser than in said first condenser, one of said first mentioned electrodes and the remaining electrode in said gaseous conduction device being connected to said second condenser, said last mentioned electrodes having such 25 a space relationship that the accumulated charge in said second condenser is insufficient to produce a discharge therebetween in said gaseous conduction device when no discharge occurs between 30 said first two electrodes but sufficient to produce such a discharge therebetween when a discharge takes place between said first two electrodes. 25
